UNITED STATES PATENT OFFICE.

ROBERT A. BEST, OF GRAND RAPIDS, MICHIGAN, ASSIGNOR OF ONE-HALF TO GEORGE M. FISH, OF GRAND RAPIDS, MICHIGAN.

TIRE-RIM TOOL.

1,211,662.

Specification of Letters Patent.

Patented Jan. 9, 1917.

Application filed November 15, 1915. Serial No. 61,553.

To all whom it may concern:

Be it known that I, ROBERT A. BEST, a citizen of the United States, residing at Grand Rapids, Michigan, have invented certain new and useful Improvements in Tire-Rim Tools, of which the following is a specification.

This invention relates to an improved tire rim tool which is used for contracting and expanding a split rim for automobile or other tire.

The main objects of this invention are: First, to make a rim tool which will contract or expand a split rim when the tire is to be removed from or replaced on the rim. Second, to make an improved rim tool which is simple, durable and cheap in construction and effective and efficient in operation.

Further objects, and objects relating to details and economies of construction and operation will definitely appear from the detailed description to follow.

I accomplish the objects of my invention by the devices and means described in the following specification.

The invention is clearly defined and pointed out in the claims.

A structure constituting a preferred embodiment of my invention is illustrated in the accompanying drawing forming a part of this specification, in which:

Figure I is a side elevation of my improved rim tool showing the same in position for action on a split rim, said rim being shown in position and the tool ready to contract and remove the same. Fig. II is a side elevation of my rim tool showing the same holding the rim in its contracted position. Fig. III is a detail vertical sectional elevation taken on a line corresponding to section line 3—3 of Fig. II, showing the manner in which my rim tool engages the rim, the tool appearing in full lines and the rim in section. Fig. IV is a detail horizontal section taken on a line corresponding to line 4—4 of Fig. III, showing the manner in which the hooks are held in engagement and yieldingly against the rim.

In the drawing similar reference characters refer to similar parts throughout the several views, and the sectional views are taken looking in the direction of the little arrows at the ends of the section lines.

Referring to the drawing, 1 is a turn

buckle in one end of which screws a right handed turn buckle eye rod 2, while in the other end screws a left handed turn buckle eye rod 3. Loosely carried by the loop of each eye rod is a pair of rim hooks 4. These rim hooks each have an elongated perforation 5 transverse to the direction of the engaging part of said hooks coupling the same to the eye. These hooks serve to grab the beaded portion 7 of a split demountable rim 7'. The springs 8 connect the two hooks of a single pair and serve to hold the same in a yielding engaging contact with the rim 7, as shown in Fig. III. From this construction, it is seen that when the hooks 4 are applied at opposite sides of the rim and the turn buckle is turned in a right hand direction the action of the same will draw the eye rods inwardly forcing the hooks to grab the rim, thus contracting the rim to the position shown in Fig. II. The springs 8 serve to hold the hooks yieldingly against the rim until the whole tool is drawn to a tightened position when the tension of the rim on the parts keeps them in position. In Fig. II one end of the rim joint overlaps the other end, due to the spring-like tendency of the rim when contracted, and from this position it is seen that the tire may be readily taken off. The perforations in the hooks, being transverse to the engaging portions thereof and loose upon the eye, permit the eye being disposed transverse to the direction of the rim and the hooks insure the eye taking a central position, and contacting directly with the rim guides the same and insures its effective action, making a very simple structure for this purpose.

When the rim is to be expanded before or after the tire has been replaced, as shown in Fig. II, the turn buckle is turned in a left hand direction, which forces the turn buckle eye rods outwardly. The top 9 of the eye bears against the inside of the rim and the eye rod is prevented from turning by the action of the hooks 4, which turn to a partial edgewise position against the rim and are held to the rim by the springs 8, said edgewise position is shown in Fig. I. Therefore, a continued turning of the turn buckle expands the rim into position and until the joint is securely made and fastened as in Fig. I. The turn buckle is then reversed in direction until the tool is loosened so that it may be removed.

I have conveniently shown the application of my rim tool to a split rim with a hinge connection. It is apparent, however, that with any type of split rim the tool may be easily applied and operated.

Having thus described my invention, what I claim as new and desire to secure by Letters Patent is:

1. In a tire rim tool, the combination of a central turn buckle with right and left threads, turn buckle rods with suitable eyes at their outer ends connected thereby, oppositely disposed hook members perforated and loosely carried by each of said eyes, the perforations being transverse to the engaging portions of said hooks, adapted to engage the rim of an automobile wheel, spring means for holding said hook members yieldingly in engagement with the said rim where-
20 by the hooks act on the rim to compress it when the turn buckle is operated to contract the rim, and to insure the centering of the said eyes against the rim when the turn

buckle is operated to expand the same, co-
acting for the purpose specified.

2. In a tire rim tool, the combination of a central turn buckle with right and left threads, turn buckle rods with suitable eyes at their outer ends connected thereby, oppositely disposed hook members perforated and loosely carried by each of said eyes, the perforations being transverse to the engaging portions of said hooks, adapted to engage the rim of an automobile wheel where-
35 by the hooks act on the rim to compress it when the turn buckle is operated to contract the rim, and to insure the centering of the said eyes against the rim when the turn buckle is operated to expand the same.

In witness whereof, I have hereunto set my hand and seal in the presence of two
40 witnesses.

ROBERT A. BEST. [L.S.]
